Corporation, a corporation of Indiana

Application March 9, 1942, Serial No. 433,899

11 Claims. (Cl. 250—174)

1

This invention relates to an electron control system and more particularly to an electron control system in which the effect of random fluctuations of the velocity of a stream of electrons is minimized.

In conventional electron control systems, an electron stream is generated, in which the initial velocities of the various electrons in the stream show random fluctuations. As a result of this, there are limitations in the degree of control that can be exercised upon the electron stream. Applicant's invention is directed to reduce these limitations.

In order more clearly to understand applicant's invention, it will be described as adapted to a control system whose operating characteristics result in a high ratio of transconductance to the D. C. plate current. Such control systems are particularly important for use with electron multipliers in which the A. C. component and the D. C. component of the electron stream are equally multiplied. For voltage amplification, it is necessary to operate over a substantially linear portion of the grid voltage-plate current characteristic. If a conventional control device is operated over a linear portion of its grid voltage-plate current characteristic, the ratio of the transconductance to D. C. plate current is relatively low. As a result, a large portion of the controlled electron stream consists of D. C. component. Since there is a certain maximum current density permissible in each stage of an electron multiplier, depending upon its physical size, the D. C. component of the current is a limiting factor on the use of electron multipliers in control systems, the function of which is to obtain voltage amplification of the A. C. component of an electron stream.

The object of the present invention, therefore, is to increase the control effects on a stream of electrons whose initial velocities show random fluctuations.

Another object of the present invention is to provide an electron control system having operating characteristics which result in a high ratio of transconductance to D. C. plate current.

Another object of the present invention is to provide an electron-control system which can be operated efficiently with an electron multiplier.

In accordance with the present invention, there is provided an electron control device comprising a source of electrons of varying velocities. Means are provided for controlling the flow of the electrons of varying velocities in such a manner that they are segregated in space in accordance with

2

their respective velocities. The segregated electrons are thereafter controlled by means having control effects on the segregated electrons varying in accordance with their respective velocities.

5 Finally, means are provided for utilizing the controlled electrons.

For a better understanding of the invention, together with other and further objects thereof, reference is had to the following description,

10 taken in connection with the accompanying drawings, and its scope will be pointed out in the appended claims.

In the accompanying drawings,

15 Fig. 1 is a diagrammatic sectional view of a control device in accordance with the invention;

Fig. 2 is a diagrammatic view of one embodiment of a control means adapted to be used in the control device shown in Fig. 1;

20 Fig. 3 is a diagrammatic view of another embodiment of a control means adapted to be used in the control device shown in Fig. 1; and

Fig. 4 is a graph showing the grid voltage-plate current characteristic curves for a conventional control device and for a control device 25 built according to applicant's invention.

Referring now more particularly to Fig. 1 of the drawings, there is shown an electron control device comprising an evacuated envelope 10 having a small neck portion 11 and a large neck portion 12. In the neck portion 11, there is provided a cathode 13, preferably of the type that produces a narrow emission spot. The cathode 13 is heated by a battery 14, as illustrated in Fig. 1. Adjacent the cathode 13, an electrode 16, 30 preferably in the shape of a hollow cylinder, is provided for focusing the electrons emitted by the cathode. The focusing electrode 16 is energized by a battery 17 to a potential negative with respect to the operating potential of the cathode 35 13.

An electrode 18 in the form of a Faraday cage and having an opening 19 and a perforated portion 20 is provided in the main portion of the envelope 10. The electrode 18 is energized by the 40 battery 22 to accelerate the focused electrons through the opening 19.

In order to change the path of the electrons accelerated into the Faraday cage, there is provided, preferably, coil means 23, which is connected in series with a variable resistor 24 and a battery 25. However, this invention is not limited for use with an electromagnetic means, such as the coil means 23, for changing the paths of the electrons. Electrostatic means may be 50 used for this purpose, or any other suitable means

known in the art. The coil means 23 produces a magnetic field transverse to the longitudinal axis of the main portion of the envelope 10. This magnetic field causes the electrons in the Faraday cage to travel along paths indicated at 27, 28, 29 and 30, depending upon their initial velocities. Thus, it is seen that, when the electrons from the cathode 13 reach the perforated portion 20, they are segregated in space according to their respective velocities.

Adjacent the perforated portion 20 of the accelerating electrode 18 and parallel thereto, there is provided a control member 32 which has openings of gradually increasing size with the smallest openings of the member 32 nearest the electron path indicated at 30. The control member 32 is energized by means of a battery 33, as shown in Fig. 1. A terminal 34, to which a signal may be applied, is coupled to the control member 32 by means of a condenser 35 and a leak resistor 36 is included in the circuit in conventional manner. The member 32, in cooperation with adjacent electrode 38, serves to produce control effects on electrons which pass through the perforated portion 20 and which will be described hereafter.

The electrons controlled by the member 32 may be utilized directly or they may be multiplied before being utilized. According to the preferred embodiment of applicant's control device shown in Fig. 1, there is provided an electron multiplier in the neck portion 12 of the envelope 10 which comprises a plurality of secondary electron emissive electrodes 38 and a collector 39. The electrodes 38 and the collector 39 are held at increasingly positive steady potentials, being connected by way of taps 40 arranged on a voltage divider 41. As shown in Fig. 1, the collector 39 is energized through an output resistor 42. The voltage divider is energized, preferably by a battery 43. It is evident from the description and the drawings that the control member 32 operates at a potential negative with respect to the electrode 18; the plurality of secondary electron emissive electrodes 38 operate at successively increasing potentials with respect to the potential of the control member 32, and the collector 39 operates at a potential positive with respect to the highest potential applied to the electrodes 38. The output from the collector 39 is taken from any convenient output lead, such as lead 44.

While the preferred embodiment of applicant's control device shown in Fig. 1 includes a plurality of electron multiplying stages, this control device may also be used without an electron multiplier.

Applicant's control device illustrated in Fig. 1 may also be built with other embodiments of the control member 32. One such embodiment is shown in Fig. 2 where control member 32A is of high resistance material and disposed adjacent the perforated portion 20 of the electrode 18. A voltage drop is produced across the member 32A by a battery 45 and a resistor 46 which are connected across the member 32A, as shown in Fig. 2. The member 32A is energized and has a signal applied to it in the same manner as the member 32 of Fig. 1, as is evident from Figs. 1 and 2.

The voltage drop across the member 32A created by the battery 45 is from left to right, viewing the member 32A in Fig. 2, and its effect on the electrons that pass through the perforated portion 20 is the same as the effect of the member 32.

Fig. 3 shows still another embodiment of apparatus for controlling the electrons that pass through the perforated portion 20. This appa-

ratus is adapted to be placed in the neck portion 12 in such a manner that a perforated grid member 32B is disposed adjacent the perforated portion 20. The member 32B is energized and has a signal applied to it in the same manner as the member 32 of Fig. 1. This is clearly illustrated in Fig. 3. Adjacent the member 32B, there is provided a collector 39B which is energized by a battery 47 through an output resistor 48. The output from the collector 39B is taken from any convenient output lead, such as lead 49. The collector 39B is positioned relative to the control member 32B in such a manner that the distance between the members 32B and 39B gradually increases from left to right, as is shown in Fig. 3. The positioning of the member 39B relative to the member 32B, in this manner, has the same effect on the electrons which pass through the perforated portion 20 as does the varying of the size of openings in the member 32 (Fig. 1) or in creating the voltage drop in the member 32A.

In Fig. 4, the curve 50 graphically illustrates the grid voltage-plate current characteristic of a conventional control device. The curve 51 graphically illustrates the grid voltage-plate current characteristic of applicant's control device. The slopes of the curves 50 and 51 represent, respectively, the transconductance of a conventional control device and the transconductance of applicant's control device. Since the linear portion of the curve 51 extends closer to the abscissa than the linear portion of curve 50, it is evident that it is possible to operate applicant's control device at a higher ratio of transconductance to D. C. plate current than a conventional control device and, at the same time, operate on a linear portion of the transconductance curve.

In describing the operation of applicant's invention, reference will be made to the embodiment of the invention shown in Fig. 1. Electrons from the cathode 13 are accelerated by the electrode 18 and directed through the opening 19 by the focusing electrode 16. Under the influence of the magnetic field produced by the coil means 23, the electrons within the Faraday cage travel along paths indicated at 27, 28, 29, and 30, whereby the slowest electrons, that is, the electrons with the smallest emission velocity, follow path 27, and the fastest electrons follow path 30. The electrons which pass through the perforated portion 20 are decelerated by a field between the perforated portion 20 and the member 32 created by the bias potentials applied, respectively, to the perforated portion 20 and the member 32. The velocities of these electrons are controlled finally by an effective potential in such a manner that, when the electrons reach the plane of the member 32, all of them are at the same velocity. The effective potential is produced by the bias potentials applied, respectively, to the control member 32 and the electrode 38 adjacent to the member 32 and by the variation in the size of the openings in the member 32, which has been explained hereinbefore. The segregated electrons from the perforated portion 20 are decelerated to the same velocity when they reach the plane of the member 32 because the variation in the size of the openings in the member 32 causes the effective potential to gradually decrease from left to right across the plane of the member 32. The variation in the effective potential is such that a relatively great amount of effective potential is provided in the path for the slowest segregated electrons, for example, the electrons following

the path 27, and gradually smaller amounts of effective potential are provided in the paths of the electrons of correspondingly greater velocities. As a result of decelerating the electrons in the plane of the member 32 to the same velocity, it is possible to operate applicant's control device at an extremely sharp cut-off characteristic.

It is not possible to operate a conventional control device at an extremely sharp cut-off characteristic because the electrons that pass the plane of the control grid of a conventional control device have random velocities. In order to completely stop the flow of these electrons past the control grid, it is necessary to apply a potential to the control grid of a predetermined value. If this potential of predetermined value is decreased an incremental amount, the fastest electrons will pass through the control grid. If the potential of predetermined value is decreased a further incremental amount, the next fastest electrons, along with the fastest electrons, will pass through the control grid. If the potential of predetermined value is decreased further incremental amounts, eventually all of the electrons from the fastest to the slowest will pass through the control grid. Thus, it is seen that in a conventional control device, a relatively large change in potential applied to the control grid is necessary in order to pass from a stage where no electrons are allowed to pass the control grid to a stage where all of the electrons are allowed to pass the control grid. And it necessarily follows that such devices do not have the sharp cut-off characteristics.

In applicant's control device, as has been explained hereinbefore, all the electrons in the plane of the control member 32 have the same velocities. Therefore, only a relatively small change to the potential applied to the control member 32 is necessary to change from the stage where no electrons are allowed to pass the control member 32 to the stage where all the electrons are allowed to pass the control member 32. Since only a relatively small potential change to the member 32 will permit all the electrons from the cathode to flow through the openings of the member 32, applicant's control device has an extremely sharp cut-off characteristic.

The controlled electrons which pass through the member 32 are multiplied by the plurality of electrodes 38 and are collected by the electrode 39, from which they are utilized for a useful purpose.

As has just been mentioned, where a plurality of electrons all have the same velocity when they pass a control member, it is possible to control the flow of these electrons and obtain an extremely sharp cut-off characteristic. This is illustrated by the curve 51 of Fig. 4 which, it is seen, has a linear characteristic extending far toward the abscissa. This results in a high ratio of transconductance to D. C. plate current component of the collected electron stream.

From the foregoing, it follows that an electron control device has been provided in which the effect of random fluctuations of the velocities of the stream of electrons is minimized. This is brought about by producing a stream of electrons of varying velocities in the control device, segregating in space the electrons in accordance with their respective velocities and controlling the segregated electrons with control effects varying in accordance with their respective velocities.

While there has been described what is at present considered the preferred embodiment of the

invention, it will be obvious to those skilled in the art, that various changes and modifications may be made therein without departing from the invention, and it is, therefore, aimed in the appended claims to cover all such changes and modifications as fall within the true spirit and scope of the invention.

What is claimed is:

1. An electron control device comprising a source of electrons of differing velocities, means adjacent said source for controlling the flow of said electrons from said source to segregate said electrons to follow different paths according to their respective velocities thereby to produce a velocity spectral distribution in a plane in space and means adjacent said plane for controlling said segregated electrons, said control means comprising means for establishing an electron control field of comparatively higher intensity in the higher velocity electron paths than in the lower velocity electron paths.
2. An electron control device comprising a source of electrons of differing velocities, means adjacent said source for accelerating said electrons along a predetermined path in said device, means adjacent said path for establishing a magnetic field in a direction perpendicular thereto for changing the direction of flight of said electrons whereby they follow different paths according to their respective velocities for producing a velocity spectral electron distribution in a plane in space and a member positioned adjacent said plane to effect a differing degree of control on said electrons in accordance with said velocity spectral distribution, said control means comprising means for establishing an electron control field of comparatively higher intensity in the higher velocity electron paths than in the lower velocity electron paths.
3. An electron control device comprising a source of electrons of differing velocities, means adjacent said source for controlling the flow of said electrons from said source to segregate said electrons to follow different paths according to their respective velocities thereby to produce a velocity spectral distribution in a plane in space and a member adjacent said plane and having openings of differing size decreasing in the direction of increasing velocities of said segregated electrons in said plane for controlling them in accordance with said velocity spectral distribution.
4. An electron control device comprising a source of electrons of differing velocities, means adjacent said source for controlling the flow of said electrons from said source to segregate said electrons to follow different paths according to their respective velocities thereby to produce a velocity spectral distribution in a plane in space and a resistor member in a plane parallel and adjacent to said plane for controlling said segregated electrons, the resistance across said resistor member varying in accordance with the velocities of said segregated electrons passing therethrough for establishing an electron control field of comparatively higher intensity in the higher velocity electron paths than in the lower velocity electron paths.
5. An electron control device comprising a source of electrons of differing velocities, means adjacent said source for controlling the flow of said electrons from said source to segregate said electrons in paths of flight in a predetermined pattern in accordance with their respective velocities and means including a control member and a collector spaced at an angle to said con-

trol member and adjacent thereto, said spacing being greater in the path of higher velocity electrons than in the path of lower velocity electrons to effect a differing degree of control on said segregated electrons in accordance with said pattern.

6. An electron control device comprising a cathode for emitting electrons of differing velocities, an electrode adjacent said cathode for accelerating said electrons along a path having a predetermined direction, an electromagnetic means adjacent said path for establishing a magnetic field in a direction perpendicular to said first-named direction to cause said electrons to follow differing paths according to their emission velocities thereby to produce a velocity spectral electron distribution in a plane in space, a control electrode positioned adjacent said plane for establishing an electron control field of comparatively higher intensity in the higher velocity electron paths than in the lower velocity electron paths, and an electron collector adjacent to said control electrode.

7. An electron control device comprising a source of electrons of differing velocities, means adjacent said source for determining the direction of flight of said electrons whereby they follow paths of flight distributed in a predetermined pattern according to velocity, and electron control means positioned adjacent said paths of flight, said control means comprising means for establishing an electron control field of comparatively higher intensity in the higher velocity electron paths than in the lower velocity electron paths.

8. An electron control device comprising a source of electrons of differing velocities, means in said device and accessible to said electrons for accelerating said electrons along a path having a predetermined direction, means adjacent said path for changing the direction of flight of said electrons whereby they follow paths of flight distributed in a predetermined pattern according to velocity, and a control means positioned adjacent said paths of flight, said control means comprising means for establishing an electron control field of comparatively higher intensity in the higher velocity electron paths than in the lower velocity electron paths.

9. An electron control device comprising a source of electrons of differing velocities, means adjacent said source and accessible to said electrons for accelerating said electrons along a path having a predetermined direction, means adjacent said path for establishing a magnetic field in a direction perpendicular to said first-named direction for changing the direction of flight of said electrons whereby they follow paths of flight

distributed in a predetermined pattern according to velocity, and a member positioned in a plane intersecting said paths of flight comprising a grid, the elements of which are spaced in varying degree in accordance with said pattern for establishing an electron control field of comparatively higher intensity in the higher velocity electron paths than in the lower velocity electron paths.

10. 10. An electron control device comprising an envelope, a source of electrons of differing velocities therein, means adjacent said source for controlling the flow of said electrons from said source to segregate said electrons in paths of flight distributed in a predetermined pattern in accordance with their respective velocities and means disposed in said envelope adjacent said paths for controlling said segregated electrons said control means comprising means for establishing an electron control field of comparatively higher intensity in the higher velocity electron paths than in the lower velocity electron paths.

11. An electron control device comprising an envelope, a source of electrons of differing velocities therein, means adjacent said source for accelerating said electrons along a path having a first direction, means adjacent said path for changing the direction of flow of said electrons to segregate said electrons in paths of flight distributed in a predetermined pattern in accordance with their respective velocities and means disposed in said envelope adjacent said paths for controlling said segregated electrons, said control means comprising means for establishing an electron control field of comparatively higher intensity in the higher velocity electron paths than in the lower velocity electron paths.
